UNITED STATES PATENT OFFICE.

HUGO POPPER, OF CHICAGO, ILLINOIS.

DESIGN FOR A CUTTING-BLADE FOR CAN-OPENERS.

46,886.

Specification for Design.

Patented Jan. 26, 1915.

Application filed November 5, 1914. Serial No. 870,523. Term of patent 7 years.

To all whom it may concern:

Be it known that I, HUGO POPPER, citizen of the United States, residing at Chicago, in the county of Cook and State of Illinois, have invented a new, original, and ornamental Design for a Cutting-Blade for Can-Openers, of which the following is a specification, reference being had to the accompanying drawing forming a part hereof.

This invention has for its object to provide a novel and ornamental design for a cutting blade for can openers.

The accompanying drawing illustrating my design is a perspective view of a cutting blade for can openers.

I claim:

The ornamental design for a cutting blade for can openers substantially as shown.

HUGO POPPER.
